No. 858,730.

PATENTED JULY 2, 1907.

L. J. LE PONTOIS.

ELECTRIC CURRENT INTERRUPTER FOR IGNITION SYSTEMS.

APPLICATION FILED DEC. 11, 1905.

UNITED STATES PATENT OFFICE.

LEON J. LE PONTOIS, OF NEW ROCHELLE, NEW YORK, ASSIGNOR TO POLY-PHASE IGNITION SYSTEM COMPANY, A CORPORATION OF NEW YORK.

ELECTRIC-CURRENT INTERRUPTER FOR IGNITION SYSTEMS.

No. 858,730.

Specification of Letters Patent.

Patented July 2, 1907.

Application filed December 11, 1905. Serial No. 291,263.

To all whom it may concern:

Be it known that I, LEON J. LE PONTOIS, a citizen of the Republic of France, and a resident of New Rochelle, Westchester county, New York, have invented a certain new and useful Improvement in Electric-Current Interrupters for Ignition Systems, of which the following is a specification.

The usual method of utilizing the energy of a primary current for jump spark ignition systems is to connect the circuit of said current, either in shunt or in series, with the primary of a suitable induction coil, the connection being opened and closed by a suitable current interrupter which is generally shunted by the condenser. It has been the usual method of operating said breaker heretofore by the combined action of a cam and opposed spring. Difficulties, however, have arisen, especially at high speeds of interruption, inasmuch as the contact mechanism must be substantial enough to do the work required of it and possesses, therefore, a certain amount of inertia which must be overcome by a spring having sufficient strength to close the circuit at the proper time. This results in the pounding or hammering of the contact surfaces which, when of iridium, tends to break them as crystallization develops rapidly. Another difficulty heretofore met with results from the rapid deterioration of the contact surfaces due to the arc occurring between them at the time of the break. Theoretically it is possible to prevent the formation of such arc by properly balancing the self induction of the system by a suitable condensance, but, as matter of fact, this balance is very difficult to obtain in practice being very unstable at various speeds of interruption. I have sought to overcome these difficulties by operating the interrupter positively in both directions by cams which cause the circuit to be closed very gradually and progressively without undue hammering of the contact surfaces, and to be broken very abruptly or suddenly without injury to the cams since they only have to overcome the inertia of the moving element of the interrupter instead of the same inertia augmented by the stress of the usual stiff spring. Furthermore, in addition to the use of a proper condenser, I prevent the formation of a spark at the time of current break by causing said break to take place in a bath of a non-volatile and electrically non-conductive liquid such as a light hydrocarbon oil or glycerin.

The invention will be understood by reference to the accompanying drawings in which

50 Figure 1 is an end view with the cover removed and the casing in section; Fig. 2 is a central longitudinal section showing the connection of the breaker-operating means to its shaft; and Fig. 3 is a face view of the reciprocating slide.

Similar reference numerals indicate similar parts in the several views.

The breaker or interrupter herein described has been designed more particularly for use in connection with a high tension current generator described in an application filed of even date herewith although it is capable of use in connection with any suitable source of current, and is shown as provided with means for varying the time of interruption of the current and, therefore, of the subsequent ignition.

Referring to the drawings numeral 1 designates an inclosing casing having an end cover 2. This casing is provided with an opening in which is set a bearing 3 adapted to receive one end of a shaft 4 which shaft is positively driven at a speed proportional to the speed of the internal combustion engine to which it is connected. The rotation of the shaft is utilized to operate the current interrupter or breaker. This breaker consists essentially of a slide 5 adapted to be reciprocated vertically between guide plates 6 and the outer face of the bearing 3. The slide 5 carries a stem piece 7 to the lower end of which is brazed an iridium contact point 8 which point is moved into and out of contact, by the reciprocation of the slide 5, with another iridium contact point 9 brazed upon the upper end of a light copper plunger 10, said plunger being capable of a slight vertical movement within a copper cup 11 insulated from the main casing by bushings 12. The cup 11 is partially filled with mercury the lower part of the plunger 10 being immersed therein at all times to insure a perfect contact between it and the cup 11 while said plunger is being reciprocated under the action of the stem 7 and a spring 13, the latter tending to maintain the plunger 10 normally pressed against the under face of a cap 14 which serves as a cover for the cup 11. The cap 14 is provided with notches 15 adapted to engage a spring finger 16 for the purpose of regulating the position of the iridium contact point 9 relative to iridium contact point 8. The mercury cup 11 is provided with a binding post 17 to permit of the desired electrical connections.

The reciprocation of the slide 5 is effected by two cams 18 and 19 mounted on a hub keyed to the shaft 4, said cams engaging respectively rollers 20 and 21 which rollers are carried by the slide 5 on pins 22 and 23. At a certain point in the rotation of shaft 4 in the direction of the arrow, Fig. 1, the cam 18 contacts with roller 20, the face of said cam being so cut as to impart to said slide a progressive downward movement. Toward the end of its stroke the stem 7 is moved to such position that the iridium contact point 8 thereon will be brought into contact with the iridium point 9. The plunger 10 is normally held in its uppermost position by the spring 13 and when the

downward movement of the stem 7 takes place a firm contact is secured between the two iridium points by reason of said spring opposing the further downward movement of the stem 7, the plunger 10 yielding very slightly under this pressure. At the limit of the throw of cam 18, cam 19 will contact with roller 21 imparting a quick upward movement to the slide 5. In the course of this upward movement the spring 13 forces the flange 24 of the plunger 19 against the under side of the cap 14 thereby arresting the further upward movement of said plunger. The iridium contact points 8 and 9 will then separate abruptly from each other and the current circuit will be open because of the arrest of the upward movement of the plunger 10 and the continuation of the upward movement of the slide 5. It is to be noted that by this construction the cams are not subjected to the usual wear since they have to overcome only the inertia of the slide 5, which is made very light, instead of the stress of a stiff spring heretofore. Such construction of a breaker also permits of the engine running at very high speed while maintaining perfect certainty in the time of making and breaking the circuit.

In order to vary at will the time of ignition the casing 1 is so mounted on the shaft 4 that the whole structure can be brought to any desired angular position by means of a lever 43 pivotally mounted on a stud 42 supported in an opening in a bracket 41. Although the slide 5 is generally in actual metallic contact with the mass of the casing 1 either by the cam surfaces or the guide 6 it has been found that at very high speed an insulating oil film exists between the above mentioned surfaces and the slide. In order, however, to obtain a very good ground under all conditions two copper brushes 44 are made to press against the sides of the slides by means of springs 45. When the cam 19 suddenly raises the slide 5 and thereby the contact point 8, the inertia of said slide might cause it to move to such position that the roller 21 would be brought against the low point of said cam. This is prevented by causing the rounded head 25 of the slide 5 to strike against a bumper comprising a hardened steel head 26 having a packing of rawhide 27, said rawhide packing being backed by a spring 28 bearing against a screw plug 29.

The breaker terminals are shown as supported in the lower part of the casing 1 which forms a chamber adapted to receive a body of oil 46 which serves not only to surround said terminals but which may serve as a lubricant as later described. By immersing the terminal points 8 and 9 in a bath of a non-volatile and electrically non-conductive liquid the heat of any nascent arc is readily dissipated through the mass of oil, and there is, therefore, no nucleus for the formation of an arc which would lead to the rapid destruction of the iridium points.

The oil bath 46 additionally serves as a source of lubricant for the bearing of the shaft 4. The oil is carried up to the bearing by a chain 32 resting upon and carried around slowly by its friction on said shaft. The oil after having been deposited on the shaft is carried throughout the bearing by helical ducts 33, the excess oil being returned to the latter by means of a cup 35 secured to the casing by bolts 36. The shaft 4 is formed with a sharp upturned edge 34 upon which

the oil leaking from the bearing accumulates and from which it is thrown by centrifugal action into an annular chamber 37 communicating with the latter by a duct 38.

The end plate 2 is formed with an opening closed by a transparent plate 40, the latter being secured to the cover by any suitable means, thus permitting the timely observance of any arc which might take place between the contact points 8 and 9 which arc may result from either a break down in the dielectric of the condenser or the insulation of the primary windings of the jump spark coil. The transparent plate 40 also permits observation of the level of the oil bath and of the degree of carbonization of the oil.

If other means are provided for the lubrication of the shaft bearing I may use glycerin instead of oil, as above described, within which to immerse the contact terminals. The casing is provided with an opening closed by a plug 39 to withdraw the oil or glycerin should it become unduly carbonized.

What I claim and desire to secure by Letters Patent is:—

1. In a circuit breaker the combination of two terminals the contact points of which are immersed in a bath of a non-volatile and electrically non-conductive liquid, a yielding support for one of said terminals, an insulated mercury cup into which the yieldingly mounted terminal projects at all times, and cams for positively reciprocating the other of said terminals toward and away from the yieldingly supported terminal.

2. In a circuit breaker the combination of two terminals the contact points of which are immersed in a bath of a non-volatile and electrically non-conductive liquid, a yielding support for one of said terminals, an insulated mercury cup into which the yieldingly mounted terminal projects at all times, cams for positively reciprocating the other of said terminals toward and away from the yieldingly supported terminal, and means for adjusting the position of the latter relatively to the reciprocating terminal.

3. In a circuit breaker the combination of two terminals a yielding support for one of said terminals, an insulated mercury cup into which said terminal projects to insure continuity of contact during its movement, a spring to hold said terminal in its normal position, and cams for positively reciprocating the other of said terminals toward and away from the yieldingly supported terminal.

4. In a circuit breaker the combination of two terminals adapted to be moved into and out of contact with each other, a yielding support for one of said terminals, a slide to which the other terminal is connected, cams adapted to reciprocate said slide and the connected terminal toward and away from the yieldingly supported terminal, a guide and contact brushes carried by said guide and adapted to bear against the reciprocating slide.

5. In a circuit breaker the combination of two terminals, a yielding support for one of said terminals, cams for positively reciprocating the other of said terminals toward and away from the yieldingly supported terminal, and a casing in which said parts are supported, said casing being capable of angular adjustment to vary at will the time at which the current is interrupted.

6. In a circuit breaker the combination of two terminals adapted to be moved into and out of contact with each other, a slide to which one of said terminals is connected, means for reciprocating said slide positively in both directions to bring its connected terminal into and out of contact with the other terminal, and a yielding cushion adapted to limit the movement of said slide in one direction for the purpose described.

In testimony whereof I have hereunto signed my name in the presence of two subscribing witnesses.
